UNITED STATES PATENT OFFICE.

TOWNSEND DE M. HAWKES, OF CORNING, NEW YORK.

DESIGN FOR A FRENCH-DRESSING BOTTLE.

46,500.

Specification for Design.

Patented Oct. 6, 1914.

Application filed July 16, 1914. Serial No. 851,414. Term of patent 14 years.

To all whom it may concern:

Be it known that I, TOWNSEND DE M. HAWKES, a citizen of the United States, residing at Corning, in the county of Steuben and State of New York, have invented a new, original, and ornamental Design for French-Dressing Bottles, of which the following is a specification, reference being had to the accompanying drawing, forming part thereof, which represents in perspective a bottle embodying my new design.

I claim:

The ornamental design for a French dressing bottle, as shown.

The foregoing specification signed at Corning, N. Y. this 20th day of June, 1914.

TOWNSEND DE M. HAWKES.

In presence of two witnesses:

SAMUEL HAWKES,

PETER C. WYCKOFF.
